STREET-SWEEPING MACHINE

Carl W. Mott, La Grange Park, Ill., assignor to
 Elgin Sweeper Company, Elgin, Ill., a corpora-
 tion of Illinois

Application June 28, 1946, Serial No. 680,041

3 Claims. (Cl. 15—85)

1

This invention relates to new and improved dirt bucket structure for street sweeping machines, and more particularly to such a structure which is especially adapted for use in small size or "baby" type street sweeping machines.

Among the objects of the invention is the provision of a dirt bucket structure for use in a small compact street sweeping machine where working space is very limited but the material swept up by the main sweeping broom of the machine must be carried to a dirt box within the machine at a point relatively remote from the sweeping range of the broom.

Another object is to provide a movable dirt bucket structure for a street sweeping machine wherein the dirt bucket is actuated from the opposite side of the main sweeping broom from which the sweepings are collected by the bucket.

A further object of the invention is to provide improved means for operating a movable dirt bucket in a street cleaning machine.

A still further object of the invention is to provide improved means for guiding a movable dirt bucket in a street sweeping machine.

Yet another object of the invention is to provide improved means for assuring dislodgement of dirt from the dirt bucket for quickly emptying the bucket for return to dirt-receiving position.

According to the general features of the invention, an elongated dirt bucket is supported transversely of a street sweeping machine with the mouth thereof opening toward the main sweeping broom of the machine to receive the sweepings therefrom in the forward movement of the machine along a roadway to be swept, the bucket being mounted for movement within the machine for depositing sweepings collected therein into a dirt box which has its mouth adjacent to the top of the machine.

Another feature of the invention resides in having the dirt bucket pivotally mounted rearwardly of the main sweeping broom for operative dirt receiving disposition in front of the broom and movable by reason of the pivotal mounting in an arc upwardly over the broom to a dirt box having its mouth near the top of the machine.

In accordance with another feature of the invention the dirt bucket is mounted and actuated through the medium of a leverage system fulcrummed on the rear axle of the sweeping machine and adapted to be actuated from the rear of the machine.

According to still another feature of the invention improved guiding and dirt dislodging structure is provided for the arcuately movable dirt

2

bucket so that the dirt bucket is guided smoothly within close operating clearances to the elevated mouth of the dirt box and when in full dirt discharging position is jolted for positively dislodging the dirt therefrom into the dirt box.

Other objects, features, and advantages of the present invention will be readily apparent from the following detailed description of a preferred embodiment of the invention taken together with the accompanying two sheets of drawings, in which:

Figure 1 is a more or less schematic partially sectional side elevational view of a street sweeping machine embodying the features of the dirt bucket structure of the present invention.

Figure 2 is a rear or mouth elevational view of the dirt bucket taken in substantially the plane of line II—II of Figure 1.

Figure 3 is a vertical sectional view through the dirt bucket taken substantially on the line III—III of Figure 2.

Figure 4 is a fragmentary sectional detail view taken substantially along the line IV—IV of Figure 1.

Figure 5 is an enlarged fragmentary horizontal sectional detail view taken substantially along the line V—V of Figure 1.

Figure 6 is an enlarged fragmentary sectional detail view taken substantially on the line VI—VI of Figure 1.

A dirt bucket structure embodying the features of the present invention is especially adapted for use in a self-propelled small size or "baby" street sweeping machine, on the order of that disclosed in my copending application, Serial No. 646,525 filed February 9, 1946, now Patent No. 2,505,199, dated April 25, 1950. A sweeping machine of this character may comprise a front engine or power section 10 and a rear or sweeping section 11 with a cooperatively intervening operator's cab 12.

Supporting the front power section 10 is a framework or chassis comprising structural members 13 which may also support the operator's cab 12 and afford a structural connection with the rear sweeping section 11 of the machine.

Mobility of the machine is afforded by a pair of rear driving wheels 14 supporting the sweeping section 11 and driven in suitable manner as by means of a chain and sprocket drive 15 from the power section 10, while the front of the machine is supported by a steerable wheel 16 mounted under the chassis 13. Operating control of the rear wheel drive may be effected from the cab 12 through the medium of a power transmission system including a control lever 17.

For light weight and compactness, as well as improved efficiency, the sweeping section 11 of the machine may be constructed principally from sheet metal, including side plates 18 and a top plate 19 secured together in substantially inverted U-shape to provide a housing. Support of the sweeping housing by the rear wheels is preferably effected through the medium of respective sleeves 20 secured to the lower rear edge portions of the side plates 18 and affording a mount for a rear wheel axle 21. (Figures 1, 4 and 5.) A splash guard and closure plate structure 22 at each side of the sweeping section 11 partially encloses the associated wheel 14 and the chain and sprocket mechanism 15 as well as other operating structure for the machine.

Mounted for operation partially between the forward portions of the rear wheels 14 on an axis parallel to the axle 21 and accessible through appropriate cut-out openings 23 in the lower portions of the side plates 18 is a main sweeping broom 24 of the rotary cylindrical type. This broom embodies any preferred construction and comprises radial bristles mounted about a suitable core supported by an axial shaft 25 which may be mounted in suitable fashion parallel to the axle 21 upon the rear ends of supporting arms 27 pivotally connected at their forward ends adjacent the bottom of the cab 12. Power for driving the sweeping broom 24 counterclockwise, as seen in Figure 1, in the forward motion of the sweeping machine is derived from the self-contained power source of the machine and is transmitted through suitable sprocket chains 28.

According to the present invention the dirt which is swept up by the main sweeping broom 24 as the machine is propelled forwardly along a roadway to be cleaned, is thrown forwardly into a dirt bucket 29 adapted to be actuated periodically from the dirt collecting position to a position for deposit of the collected dirt into a dirt box 30.

As best seen in Figure 1, the mouth of the dirt box 30 is preferably disposed within the upper portion of the housing defining the sweeping section 11 of the machine, and preferably above the sweeping broom 24. From its mouth, the dirt box 30 extends downwardly diagonally rearwardly to a dump door 31 which closes its lower end and forms the lower rear extremity of the sweeping section housing.

The dirt bucket 29 is preferably a little longer than and at least as long as the sweeping broom 24 and in operation extends transversely across the machine slightly forwardly of the sweeping broom and elevated slightly above the road level in such a relation to the sweeping broom as to receive efficiently the dirt normally swept tangentially forwardly and upwardly by the broom 24.

In a light weight construction of the dirt bucket 29, it is formed simply from an identical pair of end or side plates 32 and a body plate 33. The side plates 32 are trimmed to the desired contour which affords a straight vertical rear or mouth edge 34, a lower upwardly inclined lip edge portion 35, a relatively straight generally horizontal bottom portion 37, a rounded forwardly bulging edge portion 38, an upwardly and rearwardly diagonal portion 39 diverging from the bottom portion 37, and a top narrow generally horizontal portion 40. The body plate 33 is shaped to conform to all but the rear contour of the side plates 32 and is secured thereto in any suitable fashion such as by welding. This provides a strong, simple, inexpensive, light weight dirt

bucket of relatively large capacity and having a cross section, as seen in Fig. 3 conforming to the described shape of the side plates.

Means for supporting the dirt bucket 29 for movement between a dirt collecting position, as indicated in full outline in Figure 1, and a dirt discharging and depositing position over the mouth of the dirt box 30, as indicated in broken outline position in Figure 1, comprises a supporting and actuating lever structure 41 at each end of the bucket.

An effective arrangement for the lever structure 41 comprises in each instance a long flat lever arm 42 extending arcuately forwardly from adjacent the rear wheel axle 21 on an ample radius to clear the main sweeping broom 24. At their forward ends the lever arms 42 are secured fast to the respective opposite outer ends of a reinforcing and connecting bar 43 secured rigidly across the upper portion of the bucket side plates 32 and extending through and slightly outwardly therebeyond for receiving the lever arms. Thus, the lever arms 42 are rigidly secured together and to the respective opposite ends of the dirt bucket 29 and the dirt bucket is strongly reinforced by the rod 43. By preference the rod 43 is welded to the ends of the respective lever arms 42 and to the side plates 32, the latter being initially provided with suitable apertures 44 therethrough for the respective end portions of the bar 43. For light weight and yet ample securement and rigidity, the bar 43 may be formed of a tubular structure.

At their rear extremities, the long lever arms 42 are secured to respective bracket structures 45 each of which is formed with a sleeve 46 (Figure 4) by which it is journaled on the rear wheel axle 21 for free pivotal movement about the axle to swing its lever arm 42 through an oscillatory range within the dirt collecting and dirt depositing limits of the dirt bucket 29. Clearance for swinging movement of the respective lever arms 42 is afforded between the side plates 18 and the sides of the dirt box 30 (Fig. 5).

Means for oscillatory swinging of each of the dirt bucket lever structures 41 may comprise an hydraulic actuator 47 which is supported pivotally at its upper end by a pin 48 secured between the adjacent housing side wall 18 and the adjacent side wall of the dirt box 30. At its opposite end, the hydraulic actuator 47 is secured through the medium of a piston rod 49 with a short bell crank lever arm 50 extending rearwardly from the lever bracket structure 45 and formed with a bifurcated ear 51 (Figure 5) within which the end of the piston rod 49 is pivotally pinned. With this arrangement, when the hydraulic actuator 47 is operated to protract the piston rod 49, the bell crank lever arm 50 is driven to effect counter-clockwise pivotal swinging of the lever bracket structure 45 and thereby the long lever arm 42 and thus elevation of the dirt bucket 29 toward dirt depositing position at the mouth of the dirt box 30.

Both of the hydraulic actuators 47 are, of course, coordinated in operation to act simultaneously and a suitable hydraulic operating system (not shown) may be provided for control of the actuators by the operator sitting in the cab 12 of the machine.

In the dirt collecting position, the dirt bucket 29 is supported with the lower wall portion 37 thereof substantially parallel to the road surface and the upwardly diagonal surface 39 thereof disposed substantially perpendicular to a tangent

with the lower sweeping side of the broom 24 so as to provide a deflector for dirt swept thereagainst by the broom. Dirt dropping from the deflector is retained in the receptacle of the bucket formed by the horizontal wall portion 37 and the curved portion 38. The lip portion 35 of the bucket, of course, restrains the collected dirt from unintentionally leaving the bucket.

By having the dirt bucket 29 elevated rapidly to its discharge position at the mouth of the dirt box 30, little if any dirt will drop from the mouth of the bucket because of gravitational and centrifugal force during movement even though the bucket is gradually inverted in the course of its arc of movement toward discharge position. However, when the bucket comes to a halt in the discharge position, the dirt can fall therefrom substantially unimpeded because, as best seen in the broken line discharge position of Figure 1, the walls of the bucket diverge toward the mouth.

Spilling over the sides of dirt discharged from the dirt bucket into the dirt box 30 is avoided by the provision of side deflector wings 52 at the upper side edges of the dirt box.

Any dirt which may escape the lip 35 of the dirt bucket 29 or spill forwardly therefrom over the lip of the dirt box 30, is returned in front of the broom 24 by a baffle plate 53 carried by the forward lip of the dirt box and extending down to a position clearing the upper front portion of the broom. The deflector 53 serves also as a splash shield, cooperating in this respect with the bottom of the dirt box 30.

Forwardly of the operating path of the dirt bucket 29 is provided a dirt shield 54 which serves also as a transverse reinforcement for the side walls 18 of the housing of the sweeping section.

Any tendency of the dirt bucket 29 to swing transversely of the machine due to the relatively long leverage of the supporting lever arms 42 and which, of necessity are fairly thin due to the narrow clearance within which they must operate between the side walls 18 and the dirt box 30, is avoided by appropriate substantially frictionless guiding means. Herein such means comprises a roller 55 carried in each end of the dirt bucket and cooperating with a respective guide track 57 on the adjacent housing side wall 18. Each of the rollers 55 is carried by a suitable bracket 58 secured to the adjacent end plate 32 of the bucket and projecting upwardly therefrom in substantially intersecting relation to the plane of the diagonal wall 39.

The tracks 57 are each in the form of a sheet metal strip formed on an arc corresponding to the arc of movement of the dirt bucket while traveling from the dirt collecting position to the dirt depositing position. This strip may be secured to the inside face of the respective housing side wall 18 as by riveting, welding, or the like.

Means may be provided, in the present instance in association with the guide track structure 57, for limiting the movement of the dirt bucket 29 into the dirt-depositing position. Such means in the present instance also preferably comprises an expedient for jarring the dirt bucket slightly to assure quick discharge of dirt therefrom into the dirt box 30. Accordingly, each of the guide tracks 57 is formed at its upper extremity with a buffer or stop flange 59 extending inwardly at right angles therefrom into the path of the guide roller 55 traveling the respective track in the movement of the dirt bucket.

To reduce shock, each of the stop flanges 59 is provided with a resilient bumper block 60 which may be formed from suitable rubber or other resilient material acceptable for this purpose.

Such bumper block may be secured to the flange 59 by suitable means such as attachment screws or bolts 61. Thus, as the dirt bucket reaches its limit of movement, in the dirt discharging position at the mouth of the dirt box, the guide rollers 55 will strike the bumper block 60, bringing the bucket and actuating structure to relatively abrupt halt and with a moderate bump effecting a jar in the bucket, substantially softened by the resilience of the bumper block 60. Furthermore, due to the resilience of the bumper block 60 by reason of which it is somewhat compressed as the associated roller strikes it, there is also a certain rebound action tending to throw the dirt bucket structure into reverse. This causes, in addition to the jarring of the bucket as the roller initially strikes the bumper block 60, a jogging action which further assists in dislodging dirt from the bucket into the dirt box. To effectuate these purposes, of course, the bumper blocks 60 are preferably of substantial proportions.

The clearance of the dirt bucket 29 above the roadway is sufficient to accommodate sweepings propelled by a side broom 62 under the dirt bucket toward the main sweeping broom 24 which, in turn, drives the dirt into the dirt bucket. The side broom 62 may be driven from the same source of power and through similar control mechanism as the main sweeping broom 24.

Escape of dirt propelled by the brooms of the machine laterally from the space between the main broom 24 and the dirt bucket 29, is avoided by the provision of dirt guards or shoes 63 disposed just beyond the respective opposite ends of the main sweeping broom 24 and across the respective opposite ends of the space between the main broom and the dirt bucket.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. In a street sweeping machine having a rotary type main sweeping broom and a housing including side plates defining a passageway for a swingable dirt bucket, an elongated bucket structure having an open mouth facing the discharge side of said broom, said bucket structure having side walls substantially parallel to said side plates, and guide means secured to the outer side of each bucket side wall, said guide means in each instance comprising a flange secured to the respective bucket side wall and extending outwardly and upwardly from such wall and a roller secured on said flange for rotatable contact with the adjacent side plate of said housing for maintaining said bucket in spaced relation to said side plates as the bucket moves between a dirt receiving and a dirt discharge position.

2. In combination in a street sweeping machine having a rotary main sweeping broom and a housing including side plates defining a passageway for a swingable dirt bucket, an elongated bucket structure having an open mouth facing the broom, said bucket structure having side walls substantially parallel to said side plates, an upwardly projecting lip portion disposed across 75 the lower portion of the mouth of said bucket to

retain dirt thereini, guide means secured to the outer side of the bucket side walls for maintaining said walls spaced from the side plates of the machine as the dirt bucket moves from a dirt receiving to a dirt discharge position, said guide means in each instance comprising a flange secured to the respective bucket side wall and extending outwardly and upwardly from such wall and a roller secured on said flange for rotatable contact with the adjacent side plate of said housing, and resilient bumper means secured to the side plates at the discharge position for engagement by said rollers.

3. In a power sweeper machine including a frame and a sweeping broom mounted transversely in the frame immediately in front of the rear axle of the machine, a dirt bucket having a mouth directly adjacent the forward side of the broom to receive sweepings therefrom, a dirt bucket support arm pivoted on the rear axle and circumferentially curved around the broom, an inclined hopper mounted in the frame with an opening for receiving dirt from said bucket as it is pivoted on said curved support arm, said hopper having a discharge opening to the rear of the rear axle of the machine, and means at the rear side of the broom connected to said arm to actuate the arm for swinging the bucket upwardly over the broom to the discharge position.
